UNITED STATES PATENT OFFICE.

WILLIAM F. REACH, OF CHICOPEE, MASSACHUSETTS, ASSIGNOR TO A. G. SPALDING & BROS., OF JERSEY CITY, NEW JERSEY, A CORPORATION OF NEW JERSEY.

DESIGN FOR A TUBULAR ICE-SKATE.

53,047.

Specification for Design.

Patented Mar. 4, 1919.

Application filed September 18, 1918. Serial No. 254,684. Term of patent 14 years.

To all whom it may concern:

Be it known that I, WILLIAM F. REACH, a citizen of the United States, residing at Chicopee, in the county of Hampden and State of Massachusetts, have invented a new, original, and ornamental Design for Tubular Ice-Skates, of which the following is a specification, reference being had to the accompanying drawing, forming part thereof, in which—

Figure 1 is a side view of a tubular ice skate showing my new design.

Fig. 2 is a plan view, and,

Fig. 3 a rear view.

I claim:—

The ornamental design for a tubular ice skate as shown.

WILLIAM F. REACH.
